UNITED STATES PATENT OFFICE.

WILLIAM J. CITRON, OF SAN FRANCISCO, CALIFORNIA, ASSIGNOR TO SCENIC NOVELTY COMPANY, OF SAN FRANCISCO, CALIFORNIA, A CORPORATION OF CALIFORNIA.

PLEASURE-RAILWAY.

No. 845,524.

Specification of Letters Patent.

Patented Feb. 26, 1907.

Application filed October 1, 1906. Serial No. 336,911.

To all whom it may concern:

Be it known that I, WILLIAM J. CITRON, a citizen of the United States, residing in the city and county of San Francisco and State 5 of California, have invented new and useful Improvements in Pleasure - Railways, of which the following is a specification.

My invention relates to pleasure-railways, and especially to a form of amusement apparatus in which a car mounted on a stationary platform is made to vibrate in simulation of travel over a railway-track, but without actually advancing the car, by means of moving pictures on either traveling or stationary 15 screens, a pleasing, instructive, and delightful illusion of travel is produced in the minds of the occupants of the car.

The object of the present invention is to provide a novel and improved means for 20 supporting and rocking the car in such a way that it will have apparently the same easy, springy, sensitive, and more or less continuous vibrating motion of a Pullman; to provide means for producing a rumbling sound 25 and imparting a vibration to the car independent of the rocking means, and to provide means at the sides of the car whereby in the starting of the machinery of the car in motion the effect is given of pulling slowly 30 out of a station, these side illusions being generally independent of the pictorial illusions experienced as the trip progresses.

The invention consists of the parts and the construction and combination of parts, as 35 hereinafter more fully described and claimed, having reference to the accompanying drawings, in which—

Figure 1 is a side elevation of the car in partial section, certain parts being omitted. Fig. 40 2 is a front end view of the same. Fig. 3 is a plan view of the same.

A represents a car or vehicle of any suitable size, shape, or description, and provided with seats for spectators. I speak of it as a 45 "car" because it is used in presenting the illusion of taking a railway journey. This car is open at the front and sides, and arranged within the field of vision from the car are the respective front and side screens 2 3, upon 50 which movable pictures of one description or another are adapted to be projected or displayed for the purpose of producing the effect of traveling rapidly, the scenes which are portrayed on the screens being appropriate

to the section through which a trip is presumed to be taken. This car is partly supported on an underneath rigid stationary bar or timber 4, which is arranged centrally and longitudinally of the car and which is here shown as resting on the blocks 5. The car is 55 also partly supported by means of the cushions or springs 6, which are arranged on each side of the central rigid support 4. These cushions or springs 6 may be of any construction or design suitable for the purpose, and 60 they are of sufficient stiffness to support the car properly when the latter is filled, and at the same time they have sufficient spring so that by rocking the car they will give that 65 lateral oscillatory movement to the car 70 which is peculiar to ordinary car-bodies on their trucks.

The function of the central support 4 is to relieve the springs of too much weight and also to regulate the action of the springs to 75 produce the proper lateral oscillatory movement. If it was not for the central support 4 the car would be tipping in all directions on the springs and detract from the illusive effect. Secured to the under side of the bar 80 4, are a series of brackets 7, each carrying a pair of rollers 8, the several rollers being arranged in line and each pair contacting with a larger roller 9, suitably journaled in a fixed part on the foundation. The shafts of these 85 several rollers 9 carry sprockets around which the drive-chains 10 pass to rotate the shafts and rollers. Power to rotate the latter is derived from any suitable source, as the motor 11. The function of the several roll- 90 ers 9 10 is to create an obvious rumbling sound of vibration which is transmitted to the car-body in simulation of the passage of the trucks of a railway-carriage along the track-rails. The amount of the vibration in 95 the car caused by the contact of the rollers 9 8 is variable according to the pressure of the rollers 8 on the rollers 9, and this pressure may be regulated by using longer or shorter blocks 5 to support the bar 4. The amount 100 of vibration, however, from this source need not be very great, and it is desirable for reason of economy of power that the contact of the several rollers be not greater than is absolutely necessary.

Any suitable means may be employed to control the oscillating movement of the car on the springs 6. As here shown, I employ

a rock-shaft 12, extending lengthwise of the car and having rigid arms 12' on it, which arms are connected by the links 13 with the car-body. An operating-lever 14 is fixed 5 securely to the shaft 12 and extends up into the car within convenient reach of the operator, whereby he can give more or less side shake to the car according as the scenes portrayed upon the screen or the assumed 10 condition of the road-bed would appear to warrant, or he can give a continuous easy lateral vibration to the car such as is experienced in actual travel by the contact of the car-wheel flanges first with one rail and 15 then the other.

By means of the springs and levers and the central supporting-fulcrum bar the sensation of actual travel is realistically duplicated.

20 In order to produce an illusion in addition to that afforded by the projection of pictures on the front and side screens 2 3 after the journey has actually begun, I have devised a means whereby on the starting of the 25 motor and rollers in motion an impression will be given of slowly moving out of the station. This illusion is produced by means of a pair of side curtains 15, arranged contiguous to the windows on each side of the 30 car and painted in simulation of the interior of a station or the like. These curtains 15 are drawn down parallel with the length of the car, and before the car starts and while the car is filling with passengers the curtains 35 15 obstruct the entire view of the scenes 3 beyond. As the machinery is started suitable mechanism is set in operation which draws these curtains 15 backward, giving the effect of movement outward from the station. This mechanism for 40 operating the curtains 15 is preferably connected with and controlled by the means which produce the rumbling sound underneath the car.

45 A convenient arrangement for operating the curtains 15 is shown as follows: The shaft 16 of the rearmost roller 9 extends out to each side of the car and carries at each end the fast and loose pulleys 17 18. From 50 shaft 16 motion is transmitted when required to the alined counter-shafts 19 by the belts 20, which pass around respective of the pulleys 17 18 and the broad-faced pulleys 21 on shafts 19. Suitable belt-shifters 22 are 55 adapted to act on the belts 20 to shift both belts simultaneously from the loose pulleys 17 to the fast pulleys 18, and vice versa. These belt-shifters are here shown as pivoted at 22' and connected together by a rod 23. 60 One of them has a handle 24, extending inside the car within reach of the operator.

The curtains 15 are mounted to run on tracks 25, which extend at front and back and around the rear ends of the side screens 65 3, the curtains being shown as having the top

and bottom hooks 26 to engage the tracks to properly stretch and support the curtains.

27 are rollers at the rear end of the side screens around which the curtains 15 pass.

The rear end of each curtain or what is the 70 rear end when the curtains are drawn forward to shut out the view of the side screens passes around the rollers 27 and is attached to pull-cord 28, which runs forward around a direction pulley 29 and then downward 75 around another direction pulley 30, back to a spool or drum 31 on a respective shaft 19.

When the car is stationary and filling with people, the curtains 15 are drawn forward at the sides of the car and in front of the 80 screens 3. Being suitably painted the curtains 15 present the appearance of the interior of the station.

As soon as the motor is started and the 85 rumble of the wheels 8 9 is heard the operator throws the handle 24 to shift the belts 20 simultaneously from their normal position on the loose pulleys 17 onto the fast pulleys 18. This shifting of the belts immediately sets the shafts 19 and drums 31 90 in motion to wind up the cords or cables 28 and pull the curtains 15 from in front of the screens 3 around back of the latter. However, as the front end of the curtains 15 come abreast of the rear of the car and uncover the entire area of the screens 3 to view 95 the belts 20 are again shifted onto the loose pulleys 17 to allow the curtains to come to rest. This stoppage of the curtains 15 is preferably done automatically. As here 100 shown, one curtain has attached to it, near its front end and bottom edge, a wedge or cam 32, which is adapted to engage one of the shifters 22, suitably arranged in the path of the cam, rock the shifters, and consequently 105 throw both belts out of action. This gradual retrograde movement of the "depot" curtains 15 is succeeded by a series of illuminated scenes on the side and front screens 2 3, giving a most realistic effect of entry on 110 a journey. The present invention has nothing to do with the scenes or illusions presented on the screens 2 3.

Having thus described my invention, what I claim, and desire to secure by Letters Patent, is—

1. In a pleasure apparatus, a stationary car mounted for oscillation on a spring-support, means to oscillate the car, and means to create a rumbling sound and vibration in 120 the car like travel over a roadway without advancing the car.

2. A spring-supported vehicle open at the sides, means to rock the vehicle, draw-curtains at the sides of the vehicle, mechanism to create a rumbling sound like travel over a railway-track, and connections between said mechanism and said draw-curtains to operate the latter.

3. A car partly mounted on a stationary 130

support and partly mounted on springs, and means to control the oscillation of the car on said springs and support.

4. A vehicle supported at each side of its center on underneath springs and centrally fulcruming on a relatively unyielding support.

5. A vehicle supported at each side of its center on underneath springs and centrally 10 fulcruming on a relatively unyielding support, and means to rock said vehicle on said fulcrum.

6. A car mounted for oscillation on an underneath central support, cushion means 15 supporting the car on each side of said central support, and means extending inside the car to control the oscillations of the car.

7. A car mounted to fulcrum centrally on a stationary support, springs supporting 20 the car on each side of said central support, rollers carried by said central support and contacting with other rollers, and means to revolve the rollers to create a rumbling sound like the travel of wheels over a track.

8. The combination with a vehicle open 25 at the sides, mechanism underneath the car to create a rumbling sound and vibration in simulation of travel, normally stationary draw-curtains at the sides of the cars, and means for operating said curtains by said 30 mechanism underneath the car.

9. The combination with a car open at the sides, draw-curtains at the sides of the car, rollers underneath the car to create a rumbling sound in simulation of travel, means 35 to revolve said rollers, connections between said curtains and rollers to operate the curtains, and means for automatically disrupting said connections on the withdrawal of 40 said curtains.

In testimony whereof I have hereunto set my hand in presence of two subscribing witnesses.

WILLIAM J. CITRON.
